Geo B. Willcox, ATTORNEY

UNITED STATES PATENT OFFICE.

FRANK FOUNTAIN, OF CHARLEVOIX, MICHIGAN.

TRAP-DOOR LIFTER.

SPECIFICATION forming part of Letters Patent No. 739,301, dated September 22, 1903.

Application filed December 18, 1902. Serial No. 135,816. (No model.)

To all whom it may concern:

Be it known that I, FRANK FOUNTAIN, a citizen of the United States, residing at Charlevoix, in the county of Charlevoix and State 5 of Michigan, have invented certain new and useful Improvements in Trap-Door Lifters; and I do hereby declare the following to be a full, clear, and exact description of the invention, such as will enable others skilled in 10 the art to which it appertains to make and use the same.

This invention is a trap-door lifter.

It comprises an adjustable device adaptable to any trap-door which operates below 15 the door to automatically lift and hold it upright when released by a simple latch.

Similar numerals of reference refer to similar parts in the accompanying drawings, in which—

20 Figure 1 is an elevation, broken away in parts, of a trap-door operated by my device. Fig. 2 is a section on the line xx of Fig. 1 with parts broken away. Fig. 3 is a part sectional side view of the lifter detached, and Fig. 4 is 25 a bottom view of the lifter.

The construction and operation of the device are as follows:

A bent lever 1 is pivotally supported near its middle below the hinged edge of the door 30 2. The lifting-arm 1^a extends under the door and carries a roller 3 near its front end adapted to roll on the under face of the door as it lifts. The opposite or weight arm 1^b of the lever carries an adjustable counterweight 4. 35 This weight may be secured in different positions to balance doors of different sizes.

The lifting-lever may be supported in any suitable manner; but I prefer to support it by a bracket 5, secured to the door-frame 2^a. 40 This bracket has a vertical slot to take the pivoted lug 1^c of the lever.

The roller 3 is carried at the outer end of a double bar 6, which is secured to the end of the arm 1^a by through-bolts 7. Slotted holes 1^d permit the bar 6 and roller 3 to be 45 adjusted lengthwise to suit doors of different widths.

To hold the lifter down when the door is closed, as shown by dotted lines in Fig. 2, I 50 provide a plate 8, having a slot 8^a to engage the spring-actuated latch 9, secured to the door-frame. The plate 8 has on each side a

backwardly-extending flange 8^b, through which a set-bolt 8^c is threaded. The ends of the set-bolts 8^c bear against the sides of the 55 bar 6 and clamp the plate 8 to the bar. By unscrewing the set-bolts 8^c the plate 8 can be raised or lowered and can be clamped in a new position by tightening the bolts. As the lifting-arm is free from the door when the 60 latter is closed, the plate 8 can be so adjusted upon the lifting-arm that the roller will not lift up on the door, but will be held a short distance below it when the slot 8^a of the plate 8 engages the latch 9, thereby permitting the 65 weight of the door to rest on the frame 2^a instead of on the latch and bringing the upper surface of the door flush with the floor-line.

The roller is fixed on a spindle 10, turning in holes in the double bar. The ends of the 70 spindle project beyond the sides of the bar, and a pair of brackets 11 on the under side of the door 2, carrying depending slotted flanges 11^a, receive the ends of the spindle 10 as the door lifts. By this means the door is held 75 upright when open and locked against any tendency to fall over backward.

The latch 9 is operated by a cord 12, passing over guide-pulleys 13 within the wall and winding on a shaft 14, projecting into the 80 room at a convenient height near the door and provided with a knob 14^a for its rotation. A turn of the knob withdraws the latch and releases the lifter, which carries the door to an upright position and holds it there. 85

By the means above described I have constructed a lifter adjustable to trap-doors of different sizes which when released operates easily to gently lift the door and hold it upright. The device is capable of being so accurately balanced as to operate without noise or jar, enabling the door to be closed by slight pressure from above.

What I claim as my invention, and desire to secure by Letters Patent, is—

1. A trap-door lifter comprising in combination a vertically-movable lever pivotally mounted below the hinged edge of the door, having a lifting-arm extending forwardly under the door and a rearwardly-extending weight-arm; a roller carried by the lifting-arm and adapted to roll on the under side of the door; and means for locking and releasing the lever; and a bracket secured to the 110

- under side of the door adapted to engage a projection from the lifting-arm to hold the door upright when open.
2. A trap-door lifter comprising in combination a vertically-movable lever pivotally mounted below the hinged edge of the door, having a lifting-arm extending forwardly under the door and a rearwardly-extending weight-arm; a weight adjustable lengthwise of the weight-arm; a roller carried by the lifting-arm, adjustable lengthwise thereof and adapted to roll on the under side of the door; a spindle in the roller having its ends projecting beyond the sides of the lifting-arm; brackets secured to the under side of the door adapted to engage the ends of the spindle as the door opens to hold the door upright; a plate carried at the end of the lifting-arm and having a slot; means for adjusting the plate vertically on the end of the lifting-arm; a spring-actuated latch secured to the door-frame and adapted to engage the slotted plate on the lifting-arm.
3. In combination with a trap-door lifter of the class described having a lever pivotally supported below the edge of the door and having a weight-arm and a lifting-arm of the class described; a bracket carried by the door and adapted to engage a projection from the lifting-arm and to hold the door upright when open and to be out of engagement with said projection when the door is closed.
4. In a trap-door lifter, having a lifting-arm of the class described; a plate secured to the free end of the lifting-arm, said plate being formed with a slot adapting it to engage a latch; and means for adjusting said plate vertically transverse the lifting-arm, for the purpose set forth. 55
5. In combination with a trap-door lifter having a lifting-arm of the class described a pin extending beyond the sides of the lifting-arm and a pair of brackets secured to the under side of the door having depending flanges with slots therein adapted to engage the ends of said pin as the door opens for the purpose set forth. 40
6. In a trap-door lifter having a lifting-arm of the class described; a plate having a slot adapting it to engage a latch, secured to the end of the lifting-arm; said plate being formed with a pair of backwardly-extending flanges, one on each side of the lifting-arm, and having a pair of set-screws one threaded through each flange and bearing against the lifting-arm securing the plate thereto and permitting its adjustment thereon. 50

In testimony whereof I affix my signature in presence of two witnesses.

FRANK FOUNTAIN.
